UNITED STATES PATENT OFFICE.

LLOYD E. WISE, OF JULESBURG, COLORADO.

SIGN.

1,413,248.

Specification of Letters Patent. Patented Apr. 18, 1922.

Application filed July 9, 1921. Serial No. 483,557.

To all whom it may concern:

Be it known that I, LLOYD E. WISE, a citizen of the United States, residing at Julesburg, in the county of Sedgwick and State of Colorado, have invented certain new and useful Improvements in Signs, of which the following is a specification, reference being had therein to the accompanying drawing.

- 10 The invention relates to signs and has for its object to provide a sign particularly adapted for use on road sides for displaying various detachable sign members having printed or written thereon, articles a farmer wants to buy, or articles he desires to sell. Also to so construct such a sign that it may be easily read when approached from straight ahead or from a vehicle passing along the road adjacent said sign.
- 15 A further object is to provide an angularly shaped sign, said angularly shaped sign having its angularly disposed sides provided with struck out substantially triangularly shaped lugs, said lugs being in parallel relation to the sign and forming means for receiving extensions of detachable flexible strips forming signs, said extensions being provided with curved corners adapted to be forced behind the triangularly shaped struckout portions, and forming means for preventing upward displacement of the elongated strips until considerable pressure is applied to the lower edges of the strips for forcing the same upwardly.
- 20 A further object is to provide an angularly shaped sign, said angularly shaped sign having its angularly disposed sides provided with struck out substantially triangularly shaped lugs, said lugs being in parallel relation to the sign and forming means for receiving extensions of detachable flexible strips forming signs, said extensions being provided with curved corners adapted to be forced behind the triangularly shaped struckout portions, and forming means for preventing upward displacement of the elongated strips until considerable pressure is applied to the lower edges of the strips for forcing the same upwardly.
- 25 A further object is to provide an angularly shaped sign, said angularly shaped sign having its angularly disposed sides provided with struck out substantially triangularly shaped lugs, said lugs being in parallel relation to the sign and forming means for receiving extensions of detachable flexible strips forming signs, said extensions being provided with curved corners adapted to be forced behind the triangularly shaped struckout portions, and forming means for preventing upward displacement of the elongated strips until considerable pressure is applied to the lower edges of the strips for forcing the same upwardly.
- 30 A further object is to provide an angularly shaped sign, said angularly shaped sign having its angularly disposed sides provided with struck out substantially triangularly shaped lugs, said lugs being in parallel relation to the sign and forming means for receiving extensions of detachable flexible strips forming signs, said extensions being provided with curved corners adapted to be forced behind the triangularly shaped struckout portions, and forming means for preventing upward displacement of the elongated strips until considerable pressure is applied to the lower edges of the strips for forcing the same upwardly.
- 35 A further object is to provide an angularly shaped sign, said angularly shaped sign having its angularly disposed sides provided with struck out substantially triangularly shaped lugs, said lugs being in parallel relation to the sign and forming means for receiving extensions of detachable flexible strips forming signs, said extensions being provided with curved corners adapted to be forced behind the triangularly shaped struckout portions, and forming means for preventing upward displacement of the elongated strips until considerable pressure is applied to the lower edges of the strips for forcing the same upwardly.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

45 In the drawings:—

Figure 1 is a perspective view of the sign.

Figure 2 is a top plan view of the sign.

Figure 3 is a detail perspective view of a portion of the sign, showing one of the triangular shaped lugs for holding the end of one of the elongated sign strips.

Figure 4 is a horizontal sectional view taken on line 4—4 of Figure 3.

55 Figure 5 is a perspective view of one of the removable sign strips.

Referring to the drawings, the numeral 1 designates a sign post rectangular in horizontal cross section, and 2 a sign rectangular shaped in horizontal cross section and secured to the post by means of screws 3. The sign 2 is formed preferably from a single sheet of material and has its sides 4 disposed at right angles to each other, so that persons approaching in the direction of the arrows *a*, *b* and *c* may read the sign. The sign is of a type used in rural districts, and has displayed thereon the name 5 of the owner, and below said name information as to what the party would like to buy or sell, so that persons traveling over the road may be informed as to the wants of the owner. The items wanted or for sale are painted or otherwise placed on elongated strips 6 formed preferably from flexible material, such for instance as heavy sheet metal. The strips are provided with extensions 7 angular in front elevation, thereby forming corners 8 which are curved inwardly, there being sufficient spring action in said corners when placed in engagement with the surface of the portions 4 of the sign and forced therein, to flatten out and into the same plane as the body of the strips and when the strips are forced downwardly behind the triangularly shaped integral lugs 9, spring rearwardly through the triangularly shaped apertures 10 and hold said strips against easy displacement. The apertures 10 have their upper edges 90

11 extending upwardly and outwardly thereby forming a camming edge, which edge will assist in forcing the bent portions 8 outwardly when the strips are forced upwardly for removal purposes. However under normal conditions the bent corners 8 form means for preventing easy displacement of the strips in an upward direction. The ends of the strips 8 are so proportioned that their edges 12 will engage the inner 100 edge 13 of the triangular shaped lugs 9 and the edge 14 of the projections 7 will engage the lug 9 at the point 15 where it merges into the lug 4 of the sign. This engagement will eliminate longitudinal movement of the strips and eliminate rattling of the same.

It will be seen that a sign is provided which is triangularly shaped, formed from a single piece of material having struckout lugs for supporting elongated strips and that said strips will be held against dis-

placement. If so desired electric lights may be provided for reflecting light on the sign.

The invention having been set forth what is claimed as new and useful is:—

- 5 A display sign comprising a member having angularly disposed sections formed from a single sheet of material, spaced struck out lugs carried by said members, said spaced lugs being triangularly shaped
- 10 and disposed spaced from the members from which they are struck, removable sign strips

carried by said angularly disposed sections, said sign strips at their ends being provided with angularly tapered lugs adjacent their upper edges, the lower corners of said lugs 15 being bent inwardly, the upper edges of the triangularly shaped lugs inclining upwardly and rearwardly, said strips being formed from flexible material.

In testimony whereof I hereunto affix my 20 signature.

LLOYD E. WISE.
